CLAIM

The ornamental design for a drill bit with sleeve, as shown and described.

DESCRIPTION

FIG. 1 is a perspective view of the drill bit with sleeve showing my new design.

FIG. 2 is a front view of the drill bit with sleeve.

FIG. 3 is a rear view of the drill bit with sleeve.

FIG. 4 is a left side view of the drill bit with sleeve.

FIG. 5 is a right side view of the drill bit with sleeve.

FIG. 6 is a top view of the drill bit with sleeve; and,

FIG. 7 is a bottom view of the drill bit with sleeve.

The broken lines depict portions of the drill bit with sleeve that form no part of the claimed design.
